Des. 210,174
Patented Feb. 13, 1968

210,174

FIRE ALARM CABINET

Walter S. Franczek, Elmhurst, Ill., assignor to Lucas & Franczek, Inc., Chicago, Ill., a corporation of Illinois

Filed Sept. 15, 1966, Ser. No. 3,874

Term of patent 14 years

(Cl. D72—1)

FIGURE 1 is a front elevational view of a fire alarm cabinet showing my new design;

FIGURE 2 is an elevational view taken from one side thereof, the opposite side being a mirror image of the side shown;

FIGURE 3 is a bottom plan view thereof;

FIGURE 4 is a rear elevational view thereof; and

FIGURE 5 is a top plan view thereof.

I claim:

The ornamental design for a fire alarm cabinet, substantially as shown and described.
